UNITED STATES PATENT OFFICE

GEORGE L. VAN DINTER, OF MISHAWAKA, INDIANA, ASSIGNOR TO MISHAWAKA RUBBER AND WOOLEN MANUFACTURING COMPANY, OF MISHAWAKA, INDIANA, A CORPORATION OF INDIANA

BOOT-TOP FASTENER

Application filed April 6, 1928. Serial No. 267,840.

My invention relates to boots having a main or lower leg portion reaching substantially to the knee and an extension or top portion of relatively flexible material which 5 may be pulled upwardly over the leg above the knee or folded down around the main portion of the boot, and my invention has reference more particularly to a fastener for holding the boot top or extension in the 10 folded position.

Boots which extend above the knee are usually constructed with a main boot section or lower leg portion reaching substantially to the knee and of sufficiently stiff material 15 to be practically self sustaining in an upright position, and this main section has an extension or upper leg covering of quite flexible material, which may be pulled upwardly above the knee when desired. In 20 using boots of this character, when the full length is not required, it is customary to fold the upper portion or extension down around the main section somewhat in the form of a wide cuff, which, however, fits loosely 25 around the main section and has an undesirable tendency to work downwardly in use.

The principal objects of my invention are to provide improved means for holding the folded top of a boot against displacement; 30 to support the folded boot top by a detachable connection with the upper end of the main section of the boot; to provide a fastener which will not chafe, wear or otherwise impair the serviceability of the boot; 35 to utilize the fastener attachments as boot straps for pulling the boot on; and in general to provide simple and convenient means for supporting the folded boot top against displacement and which does not impair the 40 appearance or usefulness of the boot.

On the drawing:

Fig. 1 is a perspective view of a high top boot having the top folded down and supported by my improved fasteners; 45 Fig. 2 is an enlarged detail perspective view of one of the fastener straps;

Fig. 3 is an enlarged sectional view on the line 3—3 of Fig. 1; and

Fig. 4 is a view similar to Fig. 2, showing a modified form of fastener strap.

Referring to the drawing, the reference numeral 1 indicates the main section or lower leg portion of the boot, which has an extension 2 of relatively flexible material, secured to and forming a continuation of the upper end of the main section 1, so that it may be pulled upwardly above the knee to provide an upper leg covering. The boot in connection with which my invention is shown herein, is of the form fitting type 55 with expandible ankle and instep portion to facilitate inserting and removing the foot, and has fasteners 3 for closing together the expandible portion, but it is to be understood that this form of boot is merely used for 60 illustrating the application of my invention, which is not limited to this particular type of boot.

The upper leg covering 2 is oftentimes folded down around the section 1 in a sort of cuff like form, as shown in Figs. 1 and 3, and it is desirable to hold the folded section 3 against displacement or dropping down from the folded position. For this purpose I have provided the section 1 with a strap 4, of flexible material such as fabric or fabric and rubber, at each side of the upper end of the section 1, as shown in Fig. 1, and firmly secured between layers of material forming the section 1, as shown in Fig. 3, and these 70 straps detachably connect with the upper end of the extension 2 when the latter is folded down around the lower leg portion 1 of the boot. Any suitable fastener may be employed to connect the straps 4 with the 75 extension 2, a convenient form being the well known snap fastener, and I prefer to secure the male element or stud part 5 of the fastener to the strap and the female or socket portion 6 of the fastener to the extension 2 near the upper end substantially as shown. The strap 4, when serving to support the folded boot top, is turned downwardly over the upper edge of the boot section 1 between the portions 7 and 8 of the folded boot top, so that it is largely concealed and affords a neat and convenient fastening arrangement. Furthermore the straps 4 either in the fastened or unfastened condition, may serve the additional purpose 80

90

95

100

of boot straps for applying or pulling on the boot. These straps may also be made in the form of loops as indicated at 9 in Fig. 4, and the fastener element 10 is in this case secured to one side of the loop to permit the fingers to be inserted within the loop and between the two side portions of the folded strap 9.

With a boot top fastener of this character there are no compressing, creasing or other strains imposed on the parts of the boot and no metal parts, such as there would be if a clamp fastener were employed, that can chafe or wear or otherwise impair the serviceability of the boot, as the straps 4 or 9 loosely engage any parts with which they come in contact, and moreover, they are of flexible material which will not chafe or injure the materials of the boot. These fasteners not only support the folded boot top in an even cuff like form but they also hold the folded boot top closely against the sides of the section 1, so that chafing and interference between the boot top in walking is avoided.

While I have shown and described my invention in a preferred form, I am aware that various changes and modifications may be made without departing from the principles of my invention, the scope of which is to be determined by the appended claims.

I claim as my invention:

1. The combination with a high top boot having a main portion and an extension portion foldable down around the main portion, of a flexible member at the upper end of one of said portions detachably connecting with the upper end of the other portion for holding the extension portion in folded position.

2. The combination with a high top boot having a relatively stiff foot and leg portion with a relatively flexible tubular extension portion at the upper end thereof which folds down around the main foot and leg portion, of a member attached at the upper end of one of said portions and affording a detachable and flexible connection with the upper end of the other portion to suspend the outer fold of the folded extension portion from the upper end of the foot and leg portion.

3. The combination with a high top boot having a main portion with a strap at the upper end and an extension foldable down around the main portion, of means at the upper end of the extension detachably connecting with said strap for holding the extension in folded position.

4. The combination with a high top boot having a main portion and a tubular extension foldable down around the main portion, of a snap fastener connecting the upper end of the extension in folded position to the upper end of the main portion of the boot with the fastener at the upper end of the

folded extension and the outer layer of the folded extension suspended at its upper end from the upper end of the main portion of the boot.

5. The combination with a high top boot having a main portion and an extension foldable down around the main portion, of a strap on the main portion having a detachable connection with the extension whereby the latter is suspended in folded position from the top of the main portion of the boot.

6. The combination with a high top boot having a main portion and an extension foldable down around the main portion, of a strap at the upper end of the main portion, and means for detachably connecting the strap with the upper end of the extension for holding the latter in folded position.

7. The combination with a high top boot having a main portion and an extension foldable down around the main portion, of a pair of boot straps at the upper end of said main portion for manually pulling the boot on, and means for detachably connecting the boot straps with the extension for holding the latter in folded position.

8. The combination with a high top boot having a main portion and an extension foldable down around the main portion, of a pair of boot straps at the upper end of the main portion, and snap fasteners for connecting the upper end of the extension with the boot straps for holding the extension in folded position.

9. The combination with a high top boot having a main portion and an extension foldable down around the main portion, of a pair of loops arranged respectively at opposite sides of the main portion and at the upper end of the latter, and means for detachably connecting the loops with the upper end of the extension for holding the latter in folded position.

GEORGE L. VAN DINTER.
